UNITED STATES PATENT OFFICE.

JOHN H. HICKEY, OF SAN FRANCISCO, CALIFORNIA.

REFILLABLE FUSE.

Application filed September 29, 1926. Serial No. 138,433.

My invention relates to improvements in refillable fuses wherein a transparent fuse containing shell is arranged to be used in connection with a protective cover and detachable contact forming caps to facilitate the inspection of fuses and to effect economy in the replacing of blown fuses.

The present invention is an improvement over the device disclosed in my co-pending application, Serial No. 127,336, filed August 5, 1926, and consists of an improved construction and arrangement of elements adapted to obtain increased economy in manufacture and to facilitate and simplify the initial assembly and refilling of the fuse.

The primary object of the present invention is to provide an improved construction for refillable fuses.

Another object is to provide an improved construction which may be manufactured and assembled economically.

A further object is to provide an improved construction which will give increased strength and which may be assembled without subjecting any portion of the fuse or shell to internal strain.

Another object is to provide an improved construction whereby the shell may be removed by a simple loosening of a single set screw upon each end of the fuse and without the removal of any nut or other element likely to be lost.

A still further object is to provide an improved construction which does not require that the parts be finished to a close degree of accuracy, and which can be assembled without stressing any member of the fuse.

I accomplish these and other objects by means of the improved device disclosed in the drawings forming a part of the present application wherein like characters of reference are used to designate similar parts throughout the specification and drawings and in which,

Fig. 1 is a side elevation of my improved refillable fuse.

Fig. 2 is a longitudinal section taken at right angles to the position shown in Fig. 1.

Fig. 3 is an end elevation of the fuse drawn upon a larger scale.

Fig. 4 is a transverse section taken upon the line 4—4 of Fig. 2 in the direction indicated, and

Fig. 5 is a sectional detail showing the manner in which the evacuating tube is mounted and closed for sealing.

Referring to the drawings the numeral 1 is used to designate in general a transparent shell, preferably made of glass tubing of a desired size. Within the transparent shell 60 are mounted a pair of conductors, each comprising a disc portion 2 of a diameter substantially equal to the inside diameter of the shell 1, and a stem portion 3 extending outwardly from the ends of the shell. Lugs 4 65 extend inwardly from the portions 2 and are arranged to be connected by means of a fusible conductor 6 of predetermined current carrying capacity; said conductor 6 being riveted or otherwise secured between the lug 70 portions 4 of the conductors before said conductors are assembled into the tube.

The disc portions 2 are arranged to normally occupy positions in spaced relation to the ends of the shell 1, the space between said discs and the ends of the shell being filled with suitable cementitious material 5, such as litharge and glycerine whereby the ends may be effectively sealed. A tube 7 is connected into the shell 1 through one of 80 the discs 2, said tube being preferably made of lead or other pliant metal and is extended outwardly sufficiently to receive a connection to a pump by which the shell can be evacuated. After the ends of the shell have 85 been sealed with cement, the air is exhausted from the shell through the tube 7, which is then collapsed, as shown in Fig. 5, preferably at a point inside of the end of the shell with sufficient pressure to effect a complete 90 closure. The outer end of the tube is then cut off and the end of the tube permanently sealed by solder or by embedding within cement set to entirely close the end of the shell, as shown in Fig. 2 of the drawings. 95

A protective cover 8 is fitted around the outside of the transparent shell 1 to reinforce and strengthen said shell and to guard against breakage and possible injury to operators inserting or removing the fuse from a fuse block. Openings 10 formed in the cover permit the fusible conductor 6 to be observed through the transparent shell 1.

Contact caps 9 are fitted over the ends of the shell 1 and cover 8, said caps being provided with blades 11 arranged to engage the

contacts of a fuse block, not shown. The caps fit neatly around the ends of the shell and cover, and have bayonet slots 12 formed therein to engage pins 13 secured upon the cover to normally hold the caps in assembled relation with the shell. Lugs 14 are formed in central position upon the ends of the caps, said lugs and the blades 11 adjacent thereto being recessed as at 16 to receive the outwardly extending ends of the stems 3 of the conductors. Set screws 17 are tapped into the sides of the lugs 14 and arranged to be moved into locking engagement with the stem portions 3 to detachably lock the caps in engagement with the shell 1 and the stems 3 and to form positive electrical contact with the conductor stems.

My improved fuse, constructed as above explained, is applied and used in the ordinary manner. When in service, the fusible conductor is readily observable through the openings 10 and transparent shell 1, and the inspection of fuses and the locating of blown fuses is rendered easy. When a blown fuse is located, it is refilled by removing the caps 9 and cover 8 and inserting a new shell 1 provided with conductor members sealed into place as above explained. The caps are removed by simply loosening the set screws 17, then turning the caps to cause the pins 13 to be disengaged by the bayonet slots 12. The caps and cover are now applied upon the fresh shell and the set screws 17 tightened.

The improved construction above explained is of particular advantage as the allowable error in constructing the shells and conductors is relatively large, the depth of the recesses 16 being made sufficient to accommodate a considerable variation in the length of the shell portions 1 and the conductor stems 3. The expense of extreme accuracy is thus avoided and the task of assembling and refilling is greatly simplified. Furthermore, no strain is imposed upon the transparent shell and breakage from internal stress is entirely avoided.

The use of a metal evacuating tube sealed into the end of the shell is also of material advantage, as the expense of drawing a tip 50 onto the glass shell and the breakage due to such process is avoided. Furthermore, the metal sealing tube can be entirely embedded within the cement fillings sealing the ends of the shell, thereby avoiding possible breakage or leaking, and avoiding the necessity of heating the shell for fusing.

The above described construction is, of course, subject to modification as to the specific details of construction and arrangement and I desire to avail myself of all such modifications as may fall within the scope of the appended claims.

Having thus described my invention what I claim as new and desire to secure by Letters Patent is:

1. A refillable fuse comprising a shell; a pair of conductors mounted in longitudinally spaced relation within the shell, said conductors comprising discs fitted into the shell in spaced relation to the ends thereof, stems 70 extending outwardly from the ends of the shell, and lugs extending inwardly from the discs; a fusible conductor of predetermined current carrying capacity connected between the lugs; cement fillings set within the space between the discs and the adjacent ends of the shell to seal the same; conductive caps mounted upon the ends of the shell and arranged to engage the contacts of a fuse block; said caps being recessed to receive the outwardly extending ends of the stems; and means for detachably securing the caps in connection with the shell and in electrical contact with the stems. 75

2. A refillable fuse comprising a shell; a pair of conductors mounted in longitudinally spaced relation within the shell, said conductors comprising discs fitted into the shell in spaced relation to the ends thereof, stems 80 extending outwardly from the ends of the shell, and lugs extending inwardly from the discs; a fusible conductor of predetermined current carrying capacity connected between the lugs; cement fillings set within the space between the discs and the adjacent ends of the shell to seal the same; conductive caps mounted upon the ends of the shell and arranged to engage the contacts of a fuse block; said caps being recessed to receive the outwardly extending ends of the stems; and means for detachably securing the caps in connection with the shell and in electrical contact with the stems. 85

3. A refillable fuse comprising a transparent shell; a pair of conductors mounted in longitudinally spaced relation within the shell, said conductors comprising discs fitted into the shell in spaced relation to the ends thereof, and stems extending outwardly from the ends of the shell; a fusible conductor of predetermined current carrying capacity connected between the discs; cement fillings set within the space between the discs and the ends of the shell to seal the ends of the shell; a protective insulating cover fitted around the shell, said cover having openings therethrough to permit the observation of the fusible conductor through the transparent shell; conductive caps mounted upon the ends of the shell and arranged to engage the contacts of a fuse block, said caps being recessed to receive the outwardly extending ends of the stems; and means for detachably securing the caps in connection with the shell and conductors.

4. A refillable fuse comprising a transparent shell; a pair of conductors mounted in longitudinally spaced relation within the

shell, said conductors comprising discs fitted into the shell in spaced relation to the ends thereof, and stems extending outwardly from the ends of the shell; a fusible conductor of predetermined current carrying capacity connected between the discs; cement fillings set within the space between the discs and the ends of the shell to seal said ends; a protective insulating cover fitted around the shell, said cover having openings therethrough to permit the observation of the fusible conductor through the transparent shell; conductive caps mounted upon the ends of the shell and arranged to engage the contacts of a fuse block, said caps being recessed to receive the outwardly extending ends of the stems; means for detachably connecting the caps to the cover; and means for detachably securing the cap and forming electrical contact with the conductor stems.

5. A refillable fuse comprising a transparent shell; a pair of conductors mounted in longitudinally spaced relation within the shell, said conductors comprising discs fitted into the shell in spaced relation to the ends thereof, and stems extending outwardly from the ends of the shell; a fusible conductor of predetermined current carrying capacity connected between the discs; cement fillings set within the space between the discs and the ends of the shell to seal said ends; a protective insulating cover fitted around the shell, said cover having openings therethrough to permit the observation of the fusible conductor through the transparent shell; conductive caps mounted upon the ends of the shell and arranged to engage the contacts of a fuse block, said caps being recessed to receive the outwardly extending ends of the stems; pins secured upon the cover and arranged to engage slots formed in the adjacent portions of the caps; and set screws mounted upon the caps and arranged to engage the outwardly extended ends of the conductor stems to detachably secure the cap thereon and to form positive electrical connection therewith.

40. In a refillable fuse, the combination with a shell and a pair of spaced conductors arranged to be connected by a fusible conductor within the shell and provided with outwardly extending stems, of a pair of caps fitted over the ends of the shell, and provided with outwardly extending lugs having openings therethrough to receive the ends of the stems; and set screws carried by the lugs and arranged to engage the outwardly extended ends of the stems to form electrical contact therewith and to detachably secure the cap.

45. A refillable fuse comprising a transparent shell; a pair of conductors mounted in longitudinally spaced relation within the shell, said conductors comprising discs fitted into the shell in spaced relation to the ends thereof, and stems extending outwardly from the ends of the shell; a fusible conductor of predetermined current carrying capacity connected between the discs; cement fillings set within the space between the discs and the ends of the shell to seal said ends; a protective insulating cover fitted around the shell, said cover having openings therethrough to permit the observation of the fusible conductor through the transparent shell; conductive caps mounted upon the ends of the shell and arranged to engage the contacts of a fuse block, said caps being recessed to receive the outwardly extending

ends of the stems; means for detachably connecting the caps to the cover; and means for detachably securing the cap and forming electrical contact with the conductor stems; and a collapsible tube connected into the shell through one of the conductor discs, said tube being arranged to permit the evacuation of the shell therethrough and adapted to be collapsed for sealing said tube.

5. A refillable fuse comprising a transparent shell; a pair of conductors mounted in longitudinally spaced relation within the shell, said conductors comprising discs fitted into the shell in spaced relation to the ends thereof, and stems extending outwardly from the ends of the shell; a fusible conductor of predetermined current carrying capacity connected between the discs; cement fillings set within the space between the discs and the ends of the shell to seal said ends; a protective insulating cover fitted around the shell, said cover having openings therethrough to permit the observation of the fusible conductor through the transparent shell; conductive caps mounted upon the ends of the shell and cover and arranged to engage the contacts of a fuse block, said caps being recessed to receive the outwardly extending ends of the stems; pins secured upon the cover and arranged to engage slots formed in the adjacent portions of the caps; and set screws mounted upon the caps and arranged to engage the outwardly extended ends of the conductor stems to detachably secure the cap thereon and to form positive electrical connection therewith.

8. In a refillable fuse, the combination with a shell and a pair of spaced conductors arranged to be connected by a fusible conductor within the shell and provided with outwardly extending stems, of a pair of caps fitted over the ends of the shell, and provided with outwardly extending lugs having openings therethrough to receive the ends of the stems; and set screws carried by the lugs and arranged to engage the outwardly extended ends of the stems to form electrical contact therewith and to detachably secure the cap.

9. In a fuse, the combination with a shell, of a pair of conductors mounted within the shell and having discs of a diameter substantially equal to the inside diameter of the shell, said discs being formed integrally with the conductors and positioned in spaced relation to the ends of the shell; and cement fillings set within the ends of the shell to seal the same.

10. In a fuse, the combination with a shell, of a pair of conductors mounted within the shell and having discs of a diameter substantially equal to the inside diameter of the shell, said discs being positioned in spaced relation to the ends of the shell; and cement fillings set within the ends of the

shell to seal the same; and a collapsible tube opening into the shell through one of the discs whereby the shell may be evacuated, said tube being adapted to be collapsed to seal the evacuated shell and arranged to have its outer end embedded within the cement filling.

11. In a fuse, the combination with a shell, of caps mounted upon the ends of the shell; outwardly extending lugs carried upon the outer ends of the caps, said caps having openings opening outwardly from the shell through the lugs; current conducting means extending through the shell and having ends extending outwardly through the openings; and means carried by the lugs for detachably

securing said ends in electrical contact with the lugs.

12. In a fuse, the combination with a shell, of caps mounted upon the ends of the shell; outwardly extending lugs formed upon the outer ends of the caps, said caps having openings opening outwardly from the shell through the lugs; current conducting means extending through the shell and having ends extending outwardly through the openings; and set screws tapped into the lugs to detachably secure the ends of the conducting means in electrical contact with the lugs.

In witness whereof I hereunto set my signature.

JOHN H. HICKEY.
